UNITED STATES PATENT OFFICE.

WILLIAM E. NICKERSON, OF CAMBRIDGE, MASSACHUSETTS.

SPEED-GOVERNOR FOR ELEVATORS, &c.

SPECIFICATION forming part of Letters Patent No. 374,080, dated November 29, 1887.

Application filed June 27, 1887. Serial No. 242,691. (No model.)

To all whom it may concern:

Be it known that I, WILLIAM E. NICKERSON, of Cambridge, in the county of Middlesex and State of Massachusetts, have invented a new and useful Improvement in Speed-Governors, of which the following, taken in connection with the accompanying drawings, is a specification.

My invention relates to that class of devices in which a fluid is used for checking or regulating the speed of machines, the object being to so arrange passages in a piston that a fluid will pass freely through when the said piston is moving slowly, or at its normal speed, but be checked or restricted in its flow when the piston moves at a velocity greater than that required or desired for the proper working of the machine. This object I attain by the mechanism shown in the accompanying drawings, in which—

Figure 1 is a cross vertical section of my device, and Fig. 2 is a plan of the same.

The device that I have drawn is more especially adapted for use in connection with an elevator, although it may be used as a speed-governor for any machine.

The cylinder A may be made of any suitable material, but usually of metal. Within the cylinder A, I fit a piston, D E E', which is connected by any desirable method to the piston-rod B.

C is a screw-nut for holding the piston to its rod.

The piston, as shown in the drawings, consists of a central piece, D, to which are attached circular disks E E', by means of screws S S S S.

Packing-rings are represented by K K K K, Fig. 1.

In the piston I form a series of passages, 40 one of which is indicated by the letters P P' P² P³ P⁴ P⁵, Fig. 1. Each passage begins on the lower side of the piston at P, and traversing, as shown, forms a tortuous passage and opens on the upper side of the piston at P⁵. 45

For convenience of construction I make the piston of the three parts D, E, and E'. This method allows the parts P' and P³ of the passage to be cut or planed out, which is perhaps the cheapest way that the work can be 50 done.

I do not wish to confine myself to any particular construction, as that may be varied as desired; nor do I wish to be confined to any peculiar characteristic of form of passage, as 55 any tortuous passage will do, provided it has abrupt turns, so as to cause the current of the passing fluid to so interfere with itself as to check any rapid flow through, although when the current is slow, but little, if any, check 60 will be due to the abrupt turns in the passage.

I claim—

In a speed-governor, the combination of the cylinder A with the piston-rod B and piston composed of a central piece, as D, and disks E E', said piston having tortuous passages P P' P² P³ P⁴ P⁵, substantially as described, and for the purpose set forth.

WILLIAM E. NICKERSON.
